TRANSISTOR CUP AND WIRE LEAD ASSEMBLY
William F. Wingard, Newtonville, Mass., assignor to
United-Carr Fastener Corporation, Cambridge, Mass.,
a corporation of DelawareFiled Apr. 18, 1960, Ser. No. 22,971
1 Claim. (Cl. 174—52)

The present invention relates to an improved container for a transistor or like device and the method of staking a lead wire to the container.

In the past, lead wires were staked to transistor cups either by soldering or by forming a raised circumferential ridge a predetermined distance from the terminal end of the lead wire. The said ridge is formed with a diameter slightly larger than the diameter of the aperture formed in the said transistor cup. The lead wire is then passed between the walls of the said aperture until the ridge abuts the portion of said cup adjacent the said walls. The terminal end is then headed sandwiching the area adjacent said wall between the said ridge and the said headed portion of the lead. This method would be satisfactory if a firm engagement could be made between the cup and the lead. Unfortunately, in most cases, the wall of the aperture is badly distorted on engagement and a poor engagement is made, particularly if heat is applied, allowing the lead wire to move freely.

An object of the invention is to provide a thin walled cup and an attached lead wherein the lead is immovably engaged to said cup by a new method of engaging the lead wire with the wall of an aperture formed in the cup or container.

A further object of the invention is to provide a cup with an attached lead wire by a method wherein a portion of the wall of an aperture formed in said cup is raised to afford a good bearing surface and a local take-up of the deformation of securing the lead wire with the wall.

Other objects of the invention will, in part, be obvious, and will, in part, appear hereinafter.

In the drawing:

FIG. 1 is an enlarged top plan view of a transistor or like cup;

FIG. 2 is a section taken on the line 2—2 of FIG. 1;

FIG. 3 is a side elevation of a cup and wire lead assembled;

FIG. 4 is a top plan view of the cup and wire lead assembly shown in FIG. 3;

FIG. 5 is a section taken on the line 5—5 of FIG. 4; and

FIG. 6 is a section taken on the line 6—6 of FIG. 5.

Referring to the drawings, there is shown a cup 10 having a base 12 and a peripheral upstanding wall 14. The said wall 14 is in integral, substantially right angle relationship with said base 12. The cup 10 illustrated is in the geometric form of an octagon, however, any required geometric form may be successfully employed.

An aperture 16 is formed in the required position in the base 12. The edge 18 of the aperture 16 has a U-shaped slot 20 having a peripheral edge 22 formed therein. The opposite side of the edge 18 from the slot 20 may also be formed into U-shaped slot and its edge bent in a direction opposite to that of the peripheral edge 22. Any convenient geometric design may be utilized in forming the U-shaped slot 20. A portion of said peripheral edge 22 and the edge 18 is bent away from said base 12 to form a helix 24 which is faired gradually into the remaining portion of the edge 18 and the peripheral edge 22 as best shown in FIG. 1.

2

In a preferred form of the invention, the cup 10 is formed on a machine capable of preforming, drawing, piercing and forming operations such as an eyelet machine. An end portion of a lead wire 26 is passed through the aperture 16 between the helix 24 and the edge 18 a predetermined distance above the plane of the base 12 and into the cup 10. A heading operation is then performed, using a suitable device which heads the portion of the lead wire 26 above the plane of the base 12 into a head portion 28 while the lead wire 26 is tightly held a short distance below the said base 12 to form a circumferential shoulder 30 as shown in FIG. 5. During the heading operation mentioned heretofore, the helix 24 is forced toward the circumferential shoulder 30, and since the cup 12 is formed of soft metal, such as brass, is in effect, forced into the lead wire 26 while the edge 18 opposite the said helix 24 is forced a slightly greater distance than the said helix 24 below the plane of said base 12 as it also is pressed into the lead wire 26 as shown in FIG. 5. The result is a very strong interlocking odd shaped non-circular union between the lead wire 26 and the wall of the cup 10 as shown in FIG. 6. Of course, the aperture area defined by the peripheral edge 22, as well as the aperture 16, will be filled by an extruded portion of the lead wire 26. Once this attachment is made, the lead wire 26 can be bent to conform to requirements of circuitry without seriously disturbing the contact between the cup 10 and the lead wire 26 as has occurred in previous constructions. In fact, any displacement of one portion of the edge 18 in relation to the plane of the remaining portion of the edge 18 in either a direction above or below the plane of the base 12 will result in a successful application of the invention. We could therefore have the helix 24 formed below the plane of the base 12 and we could also have the remaining portion of the edge 18 displaced in the same direction as long as the displacement was less than the displacement of the helix 24. This would, of course, also be true if the displacement occurred above the plane of the base 12.

While the above described construction is simple and relatively inexpensive, it has proved to be a very successful construction and it should be understood that the invention relating thereto is best defined by the following claim.

I claim:

The combination of a transistor or like cup and a lead wire, said cup comprising a base and a wall, said base having an aperture formed therein, said aperture surrounded by a wall having a preformed helical portion above the plane of the remaining portion of said base, said lead wire having a terminal end extending through said aperture and above the plane of said base, said lead wire upset into positive assembled engagement with opposite faces of said cup base adjacent said aperture and said preformed helical portion being upset to lie on substantially the same plane as the remaining portion of said base and interlocked with the lead wire between the riveted portions of the wire whereby said cup and lead wire are prevented from relative rotation and to provide positive electrical connection between said lead wire and said base.
